(57) **CLAIM**

The ornamental design for a liquid extraction cleaning device, as shown and described.

DESCRIPTION

FIG. 1 is a front view of a liquid extraction cleaning device showing our new design;
 FIG. 2 is a rear view thereof;
 FIG. 3 is a right view thereof;
 FIG. 4 is a left view thereof;
 FIG. 5 is a top view thereof;
 FIG. 6 is a bottom view thereof;
 FIG. 7 is a front, right and top perspective view thereof;
 FIG. 8 is a front, left and top perspective view thereof;
 FIG. 9 is a rear, right and top perspective view thereof;
 FIG. 10 is a rear, left and top perspective view thereof;
 FIG. 11 is a front, right and bottom perspective view thereof;
 FIG. 12 is a front, left and bottom perspective view thereof;
 FIG. 13 is a rear, left and bottom perspective view thereof;
 and,
 FIG. 14 is a rear, right and bottom perspective view thereof.
